UNITED STATES PATENT OFFICE.

OSCAR A. STEERE, OF PAWTUCKET, RHODE ISLAND, ASSIGNOR TO THE HOPE WEBBING COMPANY, OF SAME PLACE.

NARROW-FABRIC LOOM.

SPECIFICATION forming part of Letters Patent No. 639,626, dated December 19, 1899.

Application filed November 14, 1898. Serial No. 696,341. (No model.)

To all whom it may concern:

Be it known that I, OSCAR A. STEERE, of Pawtucket, in the county of Providence and State of Rhode Island, have invented certain new and useful Improvements in Narrow-Fabric Looms; and I hereby declare that the following is a full, clear, and exact description of the same, reference being had to the accompanying drawings, forming part of this specification.

Positive-motion narrow-fabric looms are usually of very great length and require substantial overhead frames to support and operate the series of harnesses for forming the warp-sheds. Usually an arched frame extends the whole length of the loom, being supported on the frames at the opposite ends of the long loom. Such overhead frames require to be substantial and rigid to support the harnesses and operate them equally throughout their whole length, subjected, as they are, to the constant vibration of the running loom. These overhead work or arched frames greatly obstruct the light, and in narrow-fabric looms constructed to weave two or more sets of narrow fabric, one set above the other, the supervision over the increased number of fabrics and the increased series of warp-sheds requires better light and a more unobstructed view over the whole loom, so that any defects in the warps, such as the breaking of warp-threads, may be more readily seen by the attendant and remedied.

The invention relates to positive-motion narrow-fabric looms adapted to weave two or more series of narrow fabric one above the other.

One object of the invention is to secure an unobstructed view over all the warp in the loom; and another object of the invention is to secure more ready access to the cams operating the harnesses.

The invention consists in the peculiar and novel construction of the harness operating and supporting mechanism, whereby an unobstructed view of the warp in the loom is secured, as will be more fully set forth herein-after.

Figure 1 is a vertical transverse sectional view of the upper part of a two-set narrow-fabric loom, showing the slides in which the

ends of the harnesses are guided. Fig. 2 is a longitudinal view of the loom, showing the manner of supporting and operating the harnesses. Fig. 3 is an enlarged view showing 55 the connection with the harnesses. Fig. 4 is a transverse view showing four bell-crank levers supporting four harnesses.

Similar marks of reference indicate corresponding parts in all the figures. 60

In the drawings, *a a* indicate two warp-beams, *b b* the warp-threads for two sets of narrow fabric, one above the other, and *c c* the harnesses for controlling the warp to form the sheds for the two sets of fabrics. As this class 65 of narrow-fabric looms is very long, the harness-frames are divided into sections by vertical rods secured to the upper and lower bars of the frame.

d are the guides in which the ends of the 70 harness-frames slide up and down. These guides *d* are supported by the brackets *d'* from the inside of the end frames, as is shown in Fig. 2. *e* is the lay, and *f* the end frames, of the loom. 75

The harness-frames *c* are connected by means of a screw having a flat perforated head with the lifter-bars *g* at three or more points, and the lifter-bars are pivotally connected to the posts *g'*, and these posts are secured by a clamp-screw to the horizontal arm of the bell-crank levers *h*, whereby the same may be accurately adjusted, so as to move all parts of the harness-frames and support the same equally in all positions. The bell-crank 85 levers *h* are journaled on the shaft *h'*, supported on the frames *h''*. The vertical arms of the bell-crank levers *h h* are pivotally connected with the rods *h''*, the ends *h''* of which are each connected with the levers *i*, pivotally supported at their upper ends in a bracket secured to the end frame *f* and provided at their lower ends with a series of hooks *i'*. When connected with the lower hook *i'*, the movement of the rod *h''* is slower than when 90 the same is connected with the upper of the series of hooks *i'* of the lever *i*. The levers *i* are each provided with a stud which extends into the cam-slot *k'* on the cam-disk *k*. Each harness-frame is connected with 95 three or more of the bell-crank levers *h*, and each harness-frame is operated by a sepa-

rate rod h^3 , a separate lever i , and a separate cam-disk k . The number of cam-disks equal to the number of harness-frames used in the loom are secured to the shaft k^2 in the positions required to move the several harness-frames at the predetermined time. The cam-slot k' is formed, as shown in Fig. 2, to operate the harness-frame connected therewith four times for each revolution of the cam-disk k .

To secure the accurate movement of the bell-crank levers h , they are provided with the annular rings l , the faces of which are finished and form a bearing on the ring of the adjacent bell-crank lever, thereby holding the arms of the levers in the required position, allowing the bell-crank levers connected with different warp-frames to move independent of the adjacent levers and in a true vertical plane.

The weight of each harness-frame is counterbalanced or nearly counterbalanced by the weight h^5 , adjustably secured to the extension h^6 of the horizontal arms of the bell-crank levers h , and in the preferred form I do so counterbalance the weight of the harness-frames, and thereby reduce the friction on the cams.

By this construction the arched frames or upper works formerly used on this class of looms are removed, the upper part of the loom is cleared of all obstructions, the light from the side or top windows falls directly on the warp, and the attendant has a clear view over the whole of the loom and all parts of the warp and warp-shed.

Having thus described my invention, I claim as new and desire to secure by Letters Patent—

1. In a narrow-fabric loom, in combination, harness-frames, vertical guides for the harness-frames, bell-crank levers pivotally supported below each of the harness-frames, connections between the bell-crank levers and the harness-frames, counterweights adjustably secured to the bell-crank levers, and means, substantially as described, for operating the bell-crank levers to raise and lower the harnesses, whereby the weight of each harness-frame and the varying weight of the warp may be counterbalanced, as described.

2. In a loom, in combination, harness-frames sliding in vertical guides, two or more bell-crank levers pivotally supported below each harness-frame, said bell-crank levers

consisting of a horizontal arm extending on each side from the pivotal support in the vertical plane of the harness-frames and an arm extending vertically from the pivotal support, connections between one end of the vertical arms of the bell-crank levers and the harness-frame, counterweights adjustably secured to the vertical arms of the bell-crank levers, connections between the ends of the vertical arms of the bell-crank levers, and means, comprising grooved cam-disks, for operating the bell-crank levers to raise and lower the harness-frames, as described.

3. In a narrow-fabric loom, the combination with the series of harness-frames sliding in vertical grooves and operated from below, of frames forming the support of a shaft extending transversely to the length of the loom, a series of bell-crank levers, a counterweight adjustably secured to one of the horizontal arms of the bell-crank lever, a post adjustably secured to the other horizontal arm of the bell-crank lever, and connections between the post and the harness-frame; whereby the movement imparted to the lower end of the vertical arm of each bell-crank lever is transmitted to the harness-frame, connected with the horizontal arm of the actuated bell-crank lever, from below and the weight of each harness is counterbalanced, as described.

4. In a narrow-fabric loom, the combination with the series of harness-frames sliding in vertical guides, cams located at one end of the loom, levers engaging with the cams, frames secured to the floor below the harness-frames and shafts supported in the said frames at right angle to the harness-frames, of the bell-crank lever h , the counterweight h^5 adjustably secured to the extension h^6 , the annular rings l on each bell-crank lever controlling the path of movement of each lever, and connections between the bell-crank lever and the harness-frames and between the operating-cams at one end of the loom and the series of bell-crank levers; whereby the harness-frames throughout their whole lengths are moved in vertical planes from below, as described.

In witness whereof I have hereunto set my hand.

OSCAR A. STEERE.
